UNITED STATES PATENT OFFICE

150,753

DESIGN FOR A TEST MOUNT FOR
MINIATURE ENGINES

Elmer P. Carr, Buffalo, N. Y.

Application April 20, 1946, Serial No. 128,811

Term of patent 7 years

(Cl. D54—14)

To all whom it may concern:

Be it known that I, Elmer P. Carr, a citizen of the United States, residing at Buffalo, in the county of Erie and State of New York, have invented a new, original, and ornamental Design for Test Mount for Miniature Engines, of which the following is a specification, reference being had to the accompanying drawing, forming part thereof.

In this drawing:

Fig. 1 is a perspective view of the test mount for miniature engines, showing my new design, this view being taken from the front and left side thereof.

Fig. 2 is a rear elevation thereof.

Fig. 3 is a top plan view thereof.

Fig. 4 is a bottom elevation thereof.

Fig. 5 is a right end elevation thereof and showing the side opposite that shown in Fig. 1.

The characteristic features of the design reside in the symmetrical test mount disclosed, having the configuration, proportion and arrangement of parts specifically as shown.

I claim:

The ornamental design for a test mount for miniature engines, substantially as shown and described.

ELMER P. CARR.
